FRANK HODSON

INVENTOR.

BY

Richard B. Oliver

ATTORNEY.

UNITED STATES PATENT OFFICE.

FRANK HODSON, OF NOKOMIS, ILLINOIS.

DRILL SUPPORT.

Application filed July 9, 1921. Serial No. 483,488.

To all whom it may concern:

Be it known that I, FRANK HODSON, a citizen of the United States, residing at Nokomis, in the county of Montgomery and State 5 of Illinois, have invented certain new and useful Improvements in Drill Supports, of which the following is a specification.

This invention relates to supports for drills and has for its principal object to provide a support capable of holding a drill 10 in various positions while the same is being used.

With the foregoing general objects in view, the invention resides in the novel features of construction and unique combination of parts to be hereinafter fully described and claimed, the descriptive matter being supplemented by the accompanying drawings which form a part of this specification 20 and in which:

Figure 1 is a side elevation of the support,

Figure 2 is a sectional view taken on the line 2—2 of Figure 1 looking in the direction of the arrow,

Figure 3 is a horizontal section taken through the support on the line 3—3 of Figure 1 looking in the direction of the arrow,

Figure 4 is a detailed horizontal section taken on the line 4—4 of Figure 1 looking 30 in the direction of the arrow, and

Figure 5 is a vertical section taken on the line 5—5 of Figure 2 looking in the direction of the arrow.

Referring to the drawing in detail it will be seen that the frame consists of the two parallel standards 1 which are adapted to normally extend vertically and are connected at their ends by means of the cross bars 2. My drill support or carrier is slidably 40 mounted on the frame formed by the standards 1 and cross pieces 2. This carrier comprises the slidable clamp 3 which is provided with curved extensions 4 and 5 for grasping the standards 1. As will be noted

45 in Figure 3 there is a space provided between the extensions 4 and the post 1 for receiving a wedge key so that the slidable clamp may be securely prevented from movement in relation to the standards when 50 so desired. A second slidable clamp 7 is situated on the standards below the first clamp 3 and is also provided with the curved extensions 8 which are connected by a bar 9.

Another wedge key 10 is disposed between 55 one of the curved extensions 8 and one of the standards 1 for the purpose of fixing

this slidable clamp to the frame when so desired.

A saddle 12 is provided at one end with a curved lip 13 forming a sleeve for receiving the U-bolt 14 which is attached to the first slidable clamp 3 and thus this saddle 12 is pivotally connected to the clamp 3. A pair of spaced curved lips 15 are provided at the other end of the saddle 12 and form sleeves for receiving the pin 16 to which are pivotally attached the rods 17. The other ends of the rods 17 are pivotally connected to the rod 9.

A pair of dogs 19 are suitably mounted in 70 the first slidable clamp 3 and will be engaged with the wall or other device upon which the drill is being used. If so desired a carriage 20 may be used in connection with the saddle 12 for supporting the drill 21 75 which may be of any preferred construction and is only indicated by dotted lines in Figure 1.

In use it will be readily understood that the clamp 3 may be slid to whatever height 80 desired and then locked in position by means of the wedge key 6. The angle of the drill may then be adjusted by sliding the clamp 7 to the desired height upon the frame and locking the same in position by means of its 85 wedge key 10.

Obviously, the invention is not limited and restricted to the precise, and exact details of construction as illustrated and described, because it is susceptible of a variety 90 of embodiments, and many minor mechanical changes may be made in such preferred incorporation of the invention without departing from the substance or essence of the invention and without the sacrifice of any of 95 its substantial benefits and advantages.

Having thus described my invention what I claim as new is:—

1. In combination, a frame, a pair of slid- 100 able clamp members associated with the frame, one above the other, and provided with extensions slidably engaged with the frame, one extension on each clamp member being spaced from the frame, and wedge keys receivable between the spaced extension 105 and the frame for holding the clamp member in position on the frame, and drill supporting means supported by the clamp members.

2. In combination, a rectangular frame, a 110 pair of slidable clamp members mounted on the frame, one above the other, and each

formed with curved extensions at their ends engageable with longitudinal portions of the triangular frame, one curved extension of each clamp member being spaced from the frame, wedge keys lying along one longitudinal portion of the frame receivable between the spaced extensions and the frame for locking the clamp members in position

on the frame, and drill supporting means supported by the clamp members. ¹⁰

In testimony whereof, I affix my signature in presence of two witnesses.

FRANK HODSON.
